The specification in this patent is not in print.

H. Brunk,

Lap Anvil,

No 8,111.

Patented May 27, 1851.

Fig. 1.

Fig. 2.

UNITED STATES PATENT OFFICE.

HENRY BRUNK, OF ALBANY, NEW YORK.

LAP-ANVIL FOR SHOEMAKER.

Specification of Letters Patent No. 8,111, dated May 27, 1851.

To all whom it may concern:

Be it known that I, HENRY BRUNK, of the city of Albany and State of New York, have invented a new and useful Instrument for the Use of Boot and Shoe Makers, which I call Brink's Shoemakers' Lap - Anvil; and I declare the following specification with the drawings hereto appended as part of the same to be a full and complete description thereof.

Figure 1 exhibits a vertical section through the center of the anvil in the direction of its length. Fig. 2 exhibits a perspective view of the anvil.

From these delineations it will be seen that the instrument is a T shaped block of metal, usually of about double the size represented in the drawings, with the upper arms of the T a and b curved downward in such a manner as to adapt itself to the limbs of a workman, the shank c dropping down between his thighs, in order to be firmly grasped between them. On the top of the block there is a circular or oval shaped extension thereof upward, with a smooth upper face f forming the anvil proper. At one end on the upper edge of one of the arms is a flat-topped prismatic block e whose object is to act as a fulcrum or purchase for nippers, when stretching leather.

What I claim as my invention and desire to secure by Letters Patent is—

A metal anvil shaped substantially as set forth and described, in the within specification with its drawings; that is, with a form adapting it to be held conveniently, upon and between the knees and thighs of a workman, having a projection above the mass of metal conveniently formed into an anvil face, with a small prismatic block near the extremity of one of the arms, as a fulcrum for nippers when the same are used in stretching or manipulating leather.

HENRY BRUNK.

Witnesses:

J. B. BRINSMAN, Jr.,
RICH. VARICK DEWITT.